(57) **CLAIM**

The ornamental design for a shield for goggles, as shown and described.

DESCRIPTION

FIG. 1 is a top, front perspective view of the new design for a shield for goggles, according to a first embodiment;

FIG. 2 is a bottom, front perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is another perspective view thereof, shown in an example environment;

FIG. 10 is a top, front perspective view of the new design for a shield for goggles, according to a second embodiment;

FIG. 11 is a bottom, front perspective view thereof;

FIG. 12 is a front view thereof;

FIG. 13 is a rear view thereof;

FIG. 14 is a top view thereof;

FIG. 15 is a bottom view thereof;

FIG. 16 is a left side view thereof;

FIG. 17 is a right side view thereof; and,

FIG. 18 is another perspective view thereof, shown in an example environment.

(Continued)

The broken lines shown in the drawings illustrate environment and portions of the shield for goggles that form no part of the claimed design.
